BOGIE FOR RAILWAY ROLLING STOCK

Jakob Waldvogel and Gaston Borgeaud, Winterthür, Switzerland, assignors to Schweizerische Lokomotiv- und Maschinenfabrik, Winterthür, Switzerland

Application June 30, 1948, Serial No. 36,078
In Switzerland July 4, 1947

2 Claims. (Cl. 105—199)

1

Our present invention relates to a bogie defined in our copending application Ser. No. 764,328, now Patent No. 2,510,443, dated June 6, 1950. When, in such bogies, the weight of the vehicle-body—which is carried by the longitudinally disposed leaf-springs which are suspended laterally oscillatable—is very great, the accommodation of the said springs in the space between the wheels of the intermediate wheel-set and the minimum fixed structure presents certain difficulties. In order to obviate the latter, the present invention provides for a subdivision of each longitudinal spring pack in two individual spring packs, one of the latter being disposed outside, and the other inside of each wheel of the intermediate wheel set, and each compensator-beam or bolster is secured to the spring-ends lying in the same transverse plane, by means of an equalizer lever.

Various embodiments of our present invention are schematically shown, by way of example, in the accompanying drawing, in which

Fig. 1 shows the bogie in two cross-sections, in the left-hand portion on the line *a—a*, and in the right-hand portion on the line *b—b* in Fig. 2,

Fig. 1a is a vertical section on the line C—C of Fig. 1.

Fig. 1b is a sectional view of a type of connection J as used at various points to permit motion in a vertical direction and swinging motion of the bolster.

Fig. 2 is a plan view of Fig. 1.

Fig. 3 is a view similar to the left-hand portion of Fig. 1, of a modification.

Fig. 3a is a partial side view of Fig. 3.

Fig. 4 a top plan view of such modification, and

Fig. 5 a plan view of a modified king-pin supporting arrangement.

The truck-frame 1 is resiliently supported on the axle boxes 2 of the three truck-axes, which boxes are adapted vertically movable relative to frame 1. In Fig. 1, only the intermediate axle 3 of the three truck-axes is shown, which axle serves as free or running axle, and in Fig. 2 only the two wheels 13 of the latter are shown. The sidewalls 4 of the truck are interconnected by means of the transoms 5 both fore and aft' of the intermediate axle 3. The transoms 5 are adapted as box-girders. A compensator beam or bolster 6 is suspended laterally oscillatable from the truck-frame on the pins 8 through the swing links 7, both fore and aft' of the bogie-centre. The compensators or bolsters 6 consist of two flat beams each, which are set on edge and rigidly interconnected with each other. The ends 10 of

the bolsters are connected through the equalizers 11—which are pivoted thereto on pins 9—and by means of the pins 14 to the ends 12 of the longitudinal spring pack 15, 16 which are disposed in parallel relation both inside and outside of the wheels 13 of the intermediate axle 3.

The vehicle body 18 is supported, through shoes 21 secured thereto, on the spring pack bands 19 and 20 of the longitudinal spring pack 15 and 16, by means of lenticular intermediate plates 22, the spherical surfaces of the latter affording a good adjustability of the plane sliding-face 30. The bands 19, 20 of the spring pack 15, 16 are pivoted to the truck-frame 1 through links 24 so that they are capable of executing only lateral and vertical movements relative to the truck. The king-pin 25, which is fixed to the body 18, engages a cross-rod 26, the ends of the latter being pivoted to the rods 27 which in turn are pivoted on pins 28 to the truck. The rods 27 transmit the longitudinal forces from the body 18 onto the truck-frame 1 and vice-versa. Two further arms 33 are secured to the hub of the cross-rod 26, extending in the longitudinal direction of the vehicle, and the ends of said arms are articulated to the links 34 which in turn are pivoted to the bolsters 6 on pins 35. The two levers 26, 33 form a single wheel structure mounted in a universally tiltable relationship on a ball-shaped bush (Figs. 1 and 3) which is secured by a nut to the king pin 25. Such linkage serves for the purpose of engaging the two bolsters 6, when the vehicle-body 18 moves laterally with respect to the truck-frame 1, the bolsters 6, hanging on the swing links 7 through the pins 9, being permitted to oscillate laterally with respect to the truck-frame 1. The entire arrangement permits the truck-frame to move laterally and vertically and also to rock about a vertical axis relative to the body 18. During such latter rocking movement, the body 18 slides on the plane face 30 of the shoes 21.

It is to be understood that the type of connection J shown in Fig. 1b for the levers 26 and 27 also is representative for the connections at the points indicated; the whole for the purpose of permitting motion in a vertical direction and a swinging motion of the bolster 6.

The rigging 33—35 may be omitted, provided that the shoes 21 are positively guided. Such a modification is shown in Figs. 3, 3a and 4 in which the intermediate plates 22' are each provided with a guide-groove 36 for engaging the shoes 21', such grooves being represented in plan by circular arcs, similar to those in our said copending applica-

tion. The said grooves have their common centre coinciding with the centre of the king pin 25.

In place of the rigging 26-28 engaging the king pin, a transverse slot 38 of a common type may be provided in a longitudinal bearer 31 of the truck frame 4 for the king-pin which is provided with a slide block 39, as shown in Fig. 5.

In place of a single pin 9 for pivoting the lower end of swing link 7 and equalizer 11 to the bolster 6, a separate pin each may be provided for pivoting the said link and the said equalizer.

What we claim and desire to secure by Letters Patent is:

1. In a bogie for railway rolling stock, having three wheel-and-axle sets, a spring arrangement for suspending the vehicle body from the truck frame, comprising a spring pack on either side of each wheel of the intermediate wheel-and-axle set in a longitudinal parallel arrangement, bands secured about said spring pack, means providing a limited slidable and swivelable support for said vehicle body on said spring packs, link means for securing the band of each spring pack to the truck frame with lateral and vertical mov-

ability, a pair of rigidly interconnected bolsters both fore and aft of the said set, a two-arm equalizer lever fulcrumed at a midpoint to each end of the two pairs of bolsters and extending in the direction thereof, each end of said lever being pivoted to the corresponding end of the appurtenant spring pack in order to permit the spring pack end and the end of the said lever to rock on each other at right angles, and means 10 for oscillatably suspending the vehicle body and spring arrangement from the truck frame.

2. In a rail-vehicle bogie set out in claim 1, said means for oscillatably suspending the vehicle body and spring arrangement from the truck frame comprising a pin at each end of each pair of bolsters rigidly interconnecting the two bolsters of each pair of bolsters and serving as a fulcrum for the said equalizer lever, and swing links each pivoted at one end on the said pin and 15 20 swiveled at the other end to the truck frame.

JAKOB WALDVOGEL,
GASTON BORGEAUD.
